[57] CLAIM

The ornamental design for a butt hinge mortise guide, as shown and described.

DESCRIPTION

FIG. 1 is a top plan view of a butt hinge mortise guide showing my new design, the bottom plan view being a mirror image;

FIG. 2 is a left side elevational view;

FIG. 3 is a right side elevational view;

FIG. 4 is a front elevational view;

FIG. 5 is a rear elevational view;

FIG. 6 is a cross sectional view taken along line 6—6 of FIG. 1, shown on an enlarged scale; and

FIG. 7 is another right side elevational view, shown in a alternate position thereof.
